UNITED STATES PATENT OFFICE.

JOHN TROIDL, OF ST. LOUIS, MISSOURI.

VENDING-MACHINE.

1,138,261.

Specification of Letters Patent.

Patented May 4, 1915.

Application filed September 10, 1914. Serial No. 861,054.

To all whom it may concern:

Be it known that I, JOHN TROIDL, a citizen of the United States, residing at St. Louis, Missouri, have invented a certain new and useful Improvement in Vending-Machines, of which the following is a full, clear, and exact description, such as will enable others skilled in the art to which it appertains to make and use the same, reference being had to the accompanying drawings, forming part of this specification, in which—

Figure 1 is a perspective view of a vending machine of my improved construction. Fig. 2 is a vertical section taken approximately on the line 2—2 of Fig. 1. Fig. 3 is an enlarged vertical sectional view taken approximately on the line 3—3 of Fig. 1 and showing the coin projecting device in vertical section. Fig. 4 is a vertical section taken approximately on the line 4—4 of Fig. 3. Fig. 5 is a vertical section taken longitudinally through the center of the machine. Fig. 6 is an elevational view of the coin controlled actuating mechanism utilized in my improved machine.

My invention relates generally to vending machines and more particularly to a machine designed for vending articles of small size and shapes, such as cigars, pencils, packages of confectionery and the like.

The principal object of my invention is to provide a vending machine with mechanism whereby a purchaser or operator of the machine may, to a certain extent, test his skill in marksmanship, and in which test, a coin is utilized as the projectile, and when a "bull's-eye" is made the coin passes into the machine to control the action of the delivery mechanism, or if a "miss" is scored by the operator, the coin passes into the chute or run-way which extends to the exterior of the machine, thereby returning the coin to the operator.

Further objects of my invention are to provide a comparatively simple inexpensive vending machine which can be easily operated, which occupies comparatively little space on a showcase or counter, and which presents a neat and finished appearance.

With the foregoing and other objects in view, my invention consists in certain novel features of construction and arrangement of parts, hereinafter more fully described and claimed.

In the construction of my improved vending machine, I utilize a suitable base 1 upon

which is mounted a rectangular housing 2, preferably constructed of sheet metal, and located in the top of this housing is one or more sections of glass 3.

Formed in the upper portion of the front wall of the housing 2 is an opening 4 for the device which receives and projects the coin, and pivotally mounted on the inside of the front wall immediately behind this opening 60 is a vertically disposed slotted plate 5 which receives the coin projecting device. This device is shaped something like a pistol and comprises a handle portion 6 and a barrel portion 7, which latter is provided with a 65 longitudinally disposed passage way 8 through which the coin is projected.

Formed through the rear of the barrel portion is an opening 9 which communicates with the passage way 8, and said opening 9 70 receives the coins which are placed in the machine.

Arranged to slide in the upper portion of the handle 6 and to the rear of the barrel 8 is a block 10 having an external projection 11 whereby said block is drawn backward when the device is cocked, and bearing against the rear end of this block is a leaf spring 12. Formed on the underside of the block 10 is a shoulder 13 which, when 85 said block is drawn rearwardly, engages behind an ear 14, which latter is carried by a pivotally mounted dog 15. The lower portion of this dog has a pin and slot connection with the upper end of a pivotally 90 mounted spring pressed trigger 16, the same projecting downwardly from the handle portion of the projecting device.

The barrel portion of the projecting device projects through the opening 4 and 95 through the slot in the pivoted plate 5, and the opposite sides of said barrel portion are engaged by the round or pointed inner ends of screws 17 which are seated in the sides of the block 5, and thus the projecting device is mounted so that it may be shifted vertically or laterally, thus permitting the operator to readily shift the device when aiming at the target located at the opposite end of the housing.

100 The target comprises a vertically disposed plate 18 which depends from the top of the housing, and formed in the center of this plate is a vertically disposed slot 19 which is slightly larger than the diameter and 105 thickness of the coins utilized for operating the machine. Appearing on the face of the

plate 18 around this slot is one or more rings 20, such as are ordinarily marked upon targets, and located to the sides of said slot and projecting forwardly therefrom are 5 parallel walls 21, the forward edges of which are rounded or beveled. Arranged on the rear wall of the housing immediately to the rear of the opening 19 in the plate 18 is a bell 22 which is struck by a coin which 10 is projected through the opening 19, thereby giving an audible signal to the operator when a "bull's-eye" is scored.

Located in the upper portion of the housing between the lower portion of the plate 15 and the front wall of said housing is a hopper 23 which receives the coins which miss or are not projected through the opening 19, and leading from the discharge opening at the lower end of this hopper to one side of 20 the chamber within the housing is a chute 24. Leading from the lower end of this chute 24 is an inclined chute 25, the lower forward end of which terminates in a pocket 26, the same being located on the exterior of 25 the housing at the lower left hand corner of the front wall thereof. Thus, the hopper 23 and the chutes 24 and 25 serve as means for returning to the operator those coins which miss the "bull's-eye" and do not pass 30 into the coin controlled delivery mechanism of the machine.

Located within the chamber in the lower portion of the housing 2 and fixed to the base 1 is a pair of upright walls 27 and 28, the 35 same being connected by a rear transverse plate 29 and a front transverse plate 30. Journaled in the lower portions of the walls 27 and 28 are the trunnions of rollers 31 and arranged for operation upon said rollers is an endless belt 32.

Positioned between the walls 27 and 28 and against the front plate 30 is a rectangular container 33 for the goods or articles vended by the machine, and the open lower 45 end of this container is positioned directly over the upper portion of the belt 32.

The forward lower corner of the container 33 extends slightly beyond the front end of the rollers and said corner is cut away 50 so as to permit the discharge of the articles from the container and at a point in front of the forward one of the rollers 31.

Journalized in the walls 27 and 28 in front of the forward one of the rollers 31 is a 55 shaft 34 which carries a curved delivery pan 35, the same being adapted to receive the vended articles one at a time and carry the same downwardly in front of the forward one of the rollers 31. Located immediately below this delivery pan is an inclined plate 36 the forward end of which extends through an opening 37 formed in 60 the lower portion of the front wall of the housing. The forward end of this plate is curved upwardly, thereby forming a trough

or holder 38 into which the vended articles are delivered and from which they are removed by the operators of the machine.

Journalized in the walls 27 and 28 immediately above the shaft 34 is a shaft 39 which 70 carries an upwardly projecting finger 40, the same normally engaging directly against the front wall of the container 33. The shaft 39 is rocked in a manner hereinafter described, thereby vibrating the finger 40, 75 and consequently slightly shifting the container 33, which operation insures the proper feeding of the vended articles to the discharge opening at the lower forward corner of said container. Located on the upper 80 corner of wall 28 is a block 41 in the upper portion of which is formed a vertically disposed passage way 42, and leading rearwardly through the lower portion of said block from said vertical passage way is a 85 horizontally disposed passage way 43.

Leading from the lower end of passage way 42 downwardly through block 41 is a comparatively narrow passage way 44 which is for the purpose of permitting the 90 discharge from the coin pocket at the junction of the passage ways 42 and 43 of coins which are smaller than the ones intended for the operation of the machine.

Arranged to slide through the lower portion of the block 41 directly opposite the passage way 43 is a finger 45 to the outer end of which is pivotally connected one arm of a bell crank lever 46. This bell crank lever is fulcrumed on the plate 28 100 and pivotally connected to the lower arm thereof is a link 47 to the lower end of which is pivotally connected a lever 48, the same being fulcrumed at 49 and the forward end projecting through a slot 50 formed in 105 the lower right hand portion of the front wall of the housing 2. Located on the forward end of this lever 48 is a disk or button 51. The forward end of this lever is normally held in elevated position by means of 110 a rectangular spring 52.

Fulcrumed on the rear upper portion of plate 28 is a horizontally disposed lever 53, the rear portion of which extends between the block 41 and plate 28, and said rear portion is bent upwardly and provided with a laterally projecting pin 54, which projects through a vertically disposed slot 55 in the block 41. This pin 54 which normally occupies the lower end of slot 55 lies across the 115 upper portion of passage way 43 where it is in position to be engaged and elevated by a coin forced through said passage way.

Pivots connected to the forward end of lever 53 is the rear end of a lever 56 125 which is fulcrumed to plate 28, and the forward end of this lever is normally drawn downward by a retractile spring 57. Pivotally connected to the forward portion of lever 56 is the upper end of a vertically 130

- disposed bar 58 on the lower end of which is formed a series of rack teeth 59 which engage the teeth of a small pinion 60, which latter is mounted on the end of shaft 34.
- 5 Fixed on the corresponding end of shaft 39 is an arm 61 to the outer end of which is pivotally connected a link 62, the lower end of which latter is pivotally connected to lever 48.
- 10 Fixed on the trunnion of the forward one of the rollers 31 and outside the plate 28 is a ratchet wheel 63 and engaging the teeth thereof is the point of a spring held hooked pawl 64.
- 15 Located to the rear of plate 18 and below bell 22 is the upper end of a chute 65 which leads downwardly and laterally, the lower or discharge end of said chute terminating immediately above the upper end of passage 20 way 42.
- A door 66 forms a part of the rear wall of the housing 2, thus providing means whereby access may be readily had to the interior of said housing for the purpose of 25 refilling the container 33, removing the coins retained in the machine, and repair or adjustment of the coin controlled actuating mechanism.
- The operation of the machine is as follows: The block 10 is drawn rearwardly or 30 into cocked position by engagement of the finger against the lug 11, which action stores power in the spring 12, and when said block has been moved to its rearward limit of 35 movement, the ear 14 will engage in front of the shoulder 13. A coin of the proper denomination is now dropped through the opening 9 into the passage way 8 and the operator now aims the coin projecting device 40 vice at the slot 19 in the wall 18.
- The projecting device can readily be shifted owing to its being connected to the block 5 by a universal joint. After the projecting device has been aimed, the operator 45 pulls the trigger 16, thereby releasing the block 10 and the same is impelled forward under the action of spring 12, thereby projecting through the passage way 8 toward the plate 18 on which the target is located.
- 50 If the coin does not pass between the walls 21 and through the slot 19, it will, after striking against the plate 18, drop into the hopper 23 and pass from thence through chute 24 into and through chute 25, and will 55 finally be deposited in the pocket 26 from whence it can be removed by the operator and used again in the projecting device.
- While the projected coin passes between the walls 21 and through the opening 19 it 60 strikes against bell 22, thereby registering a "bull's-eye," after which said coin drops into chute 65 and passes downwardly therethrough and into and through the passage way 42 in block 41. The coin lodges on 65 the shoulders at the upper end of the pas-
- sage way 44, thus being directly in the path of travel of the finger 45. The operator having scored a "bull's-eye" now depresses the forward end of lever 48 by pressing on the button 51, and as a result, the rear end 70 of this lever is elevated, thereby actuating bell crank 46 and moving finger 45 through the block 41 and partially through passage way 42. This movement forces the coin through passage way 43, thereby elevating 75 pin 54 and the rear end of lever 53, and immediately thereafter, the coin is discharged through the rear end of passage way 43 into a suitable receptacle located within the housing beneath the block 41. 80 As the rear end of lever 53 is elevated the forward end thereof is depressed, thereby swinging lever 56 upon its fulcrum, and consequently slightly raising bar 58 having the rack teeth 59 which mesh with the teeth of 85 pinion 60. Thus shaft 34 is partially rocked and the plate or trough 35 carried thereby is moved downward, thus delivering one of the articles from the container 33 onto the plate or pan 36, and said article passes downwardly into the pocket 38 at the front of 90 the machine from which point it can be readily removed by the operator.
- Immediately after the depression of the lever 48, the same, together with levers 53 95 and 56 and the coöperating parts of the coin controlled mechanism are moved to their normal positions under the influence of retractile springs 52 and 57. As lever 48 is actuated the hooked pawl 64 engaging 100 ratchet wheel 63 partially rotates the same, thereby imparting corresponding movement to the forward end of the rollers 31, thus shifting the belt 32 a short distance, which movement insures the feeding of the devices 105 within the container 33 toward the discharge opening at the lower forward corner thereof.
- Simultaneously with the depression of lever 48, the shaft 39 is rocked by reason of 110 the connections 61 and 62 between said shaft and lever, thus vibrating finger 40, and consequently imparting a slight movement of container 33 rearwardly or in opposition to the feeding forward movement of the upper 115 portion of belt 32.
- It will be understood that the vibrating movement imparted to the container 33 and the intermittent feed of the belt 32 takes place every time the lever 48 is depressed. 120
- A vending machine of my improved construction is comparatively simple, is adapted for vending all small articles, such as cigars, pencils, small bottles of perfume, packages of candy and the like, and being 125 provided with a trigger and coin projecting device, the machine is attractive to those persons desiring to test their skill in marksmanship. For each coin retained in the machine, the operator receives an article from 130

the machine and as hereinbefore described, all coins which miss the target are returned to the operators.

It will be readily understood that minor changes in the size, form and construction of the various parts of my improved vending machine can be made and substituted for those herein shown and described, without departing from the spirit of my invention, the scope of which is set forth in the appended claims.

I claim:

1. In a vending machine, a container for the articles to be vended, which container has an open bottom, an endless belt arranged beneath said container and forming a bottom therefor, a trough pivotally mounted at the discharge end of the container, means for imparting intermittent movement to the belt, and coin controlled means coöperating with and operated by the belt actuating means for imparting tilting movement to the trough.

2. In a vending machine, a container for the articles to be vended, which container has an open bottom, an endless belt arranged beneath said container and forming a bottom therefor, a trough pivotally mounted at the discharge end of the container, a vibrator bearing against the container, means for imparting intermittent movement to the belt and simultaneously actuating the vibrator, and coin controlled means coöperating with and actuated by the belt and vibrator actuating means for imparting tilting movement to the trough.

3. In a vending machine, a container for the articles to be vended, a pair of rollers arranged beneath said container, a belt operating on said rollers, there being a discharge opening between one of said rollers and the end of the container, a pivotally mounted trough arranged beneath said dis-

charge opening, means for imparting movement to one of the rollers to drive the belt 45 operating thereupon, and coin controlled means coöperating with and actuated by the roller actuating means for imparting tilting movement to the trough.

4. In a vending machine, a container for 50 the articles to be vended, a pair of rollers arranged beneath said container, a belt operating on said rollers, there being a discharge opening between one of said rollers and the end of the container, a pivotally 55 mounted trough arranged beneath said discharge opening, means for imparting intermittent movement to one of said belt carrying rollers, means actuated by the roller actuating means for shifting the container 60 simultaneously with and in a direction opposite to the movement of the belt and coin controlled means coöperating with and actuated by the roller actuating means for imparting tilting movement to the trough. 65

5. In a vending machine, a container for the articles to be vended, which container is open at its lower end, an endless belt arranged beneath the container and forming a bottom therefor, a trough pivotally mounted at the discharge end of the container, means for moving the upper portion of the belt toward the trough and simultaneously moving the container in a direction opposite to that of the movement of the upper portion of the belt and coin controlled means actuated by and coöperating with the belt actuating means for simultaneously imparting tilting movement to the trough. 75

In testimony whereof I hereunto affix my 80 signature in the presence of two witnesses, this 8th day of September, 1914.

JOHN TROIDL.
